Anthony C. Fallace

*By Percy H. Moore
Attorney.*

UNITED STATES PATENT OFFICE.

ANTHONY C. FALLACE, OF CARNEYS POINT, NEW JERSEY.

DESIGN FOR A BUTTON, FLAG, EMBLEM, PENNANT, BANNER, PILLOW TOP, OR ARTICLE OF SIMILAR NATURE.

60,522.

Specification for Design.

Patented Mar. 7, 1922.

Application filed March 3, 1921. Serial No. 449,538. Term of patent 3½ years.

To all whom it may concern:

Be it known that I, ANTHONY C. FALLACE, a citizen of the United States, residing at Carneys Point, in the county of Salem and State of New Jersey, have invented a new, original, and ornamental Design for Buttons, Flags, Emblems, Banners, Pennants, Pillow Tops, or articles of similar nature, of which the following is a specification, reference being had to the accompanying drawing, forming part thereof.

The figure is a plan view of a banner showing my new design.

I claim:

The ornamental design for a button, flag, emblem, banner, pennant, pillow top, or article of similar nature.

ANTHONY C. FALLACE.
